AUTOMATIC CONTROLLER FOR INTERNAL COMBUSTION ENGINE STARTERS

Gordon B. Sayre, Syracuse, N. Y., assignor to Remowen Corporation, a corporation of New York

Application February 17, 1932, Serial No. 593,521

22 Claims. (CL 290—37)

This invention relates to new and useful improvements in automatic controllers for internal combustion engine starters, and particularly to automatic controllers that are associated with the ignition circuit of internal combustion engines.

Automatic controllers for starters of the above type are made operative upon closing the ignition switch, whereupon the starting motor circuit is energized and the starting motor proceeds to crank the engine. A system of this type has the disadvantage in that should the operator of a motor vehicle thus equipped, turn on the ignition switch while the vehicle was in gear, the operator may lose control of the same due to the sudden and unexpected motion thereof.

The main object of this invention is to provide means in automatic controllers for internal combustion engine starters for rendering the starter inoperative while the vehicle thus equipped is in gear.

Another object of this invention is to provide a means to cause the starter to crank the engine should it stall after being properly started which is independent of the position of the gear shift lever or clutch pedal.

Other objects and advantages relate to details of the controller circuit and to the arrangement of the parts thereof, all as will more fully appear from the following description, taken in connection with the accompanying drawings in which:—

Figure 1 is a diagrammatic illustration of an embodiment of my invention.

Figure 2 is a diagrammatic illustration of a modified form of my invention.

Figure 3 is a diagrammatic illustration of a further modification of my invention.

Figure 4 is a diagrammatic illustration of a controller circuit of the semi-automatic type.

This invention may be applied to various types of automatic controller circuits. For instance, in Figure 1, the system employs a sub-atmospheric pressure relay that may be controlled by vacuum conditions in the engine intake manifold which, in conjunction with a current controlled relay in the starting motor circuit, provides the automatic control of the starting motor circuit.

More specifically in Figure 1, 1 designates the usual battery, one terminal of which is grounded by wire 2. The other terminal may be connected to the ignition circuit by wire 3, ammeter 4, wire 5, ignition switch 6, wire 7, ignition coil 8 and wires 9 leading to the distributor in the usual and well-known manner.

55 A starting motor circuit is provided comprising

ing battery 1, wire 11, holding coil 12, contact 13, switch member 14, contact 15, wire 16, starting motor 17, wire 18 and return through ground to wire 2 back to battery 1.

An electro-magnetic starting switch, generally designated by arrow 19, comprises contacts 13 and 15 adapted to be bridged by switch member 14 which may be secured to armature 21 actuated in turn by coil 20. Armature 21 secured to switch member 14, normally holds the latter out of engagement with contacts 13 and 15.

The energizing circuit for electro-magnetic switch 19 consists of two branches to be herein-after respectively designated as primary and secondary circuits. Both circuits have a common portion starting with junction 22, wire 23, armature 24, contact 33, wire 34, junction 35, wire 38, coil 20 and junction 39. The primary circuit continues by way of wire 40 to normally closed contacts 41 and 42 of vacuum relay 43, in this instance, connected to the intake manifold 46 of the internal combustion engine and which is grounded through wire 47.

Vacuum relay 43, as shown, comprises a diaphragm 45 mounted within a suitable casing and normally spring-pressed by spring 53 against contact arm 44 upon which is mounted contact 42. Contact arm 44 is secured at one end to the relay casing and, normally upon the removal of the force exerted thereon by diaphragm 45, maintains contacts 41 and 42 out of engagement. The secondary circuit continues from junction 39 by way of wire 48, contact 49, armature 50 and wire 52 to ground.

A spring 51 normally holds armature 50 out of engagement with contact 49. Holding coil 12, armature 50 and contact 49 constitute a current control relay for opening and closing the secondary circuit in accordance with current conditions in the starting motor circuit. The initial energization of coil 20 of switch 19 is controlled by ignition switch 6 and the control relay constituted by armature 24, contact 33 and the two holding coils 26 and 36.

Armature 24 is normally held out of contact 45 with contact 33 by a spring 32. Holding coil 26 may be energized to produce a magnetic pull upon armature 24 thereby overcoming the tension of spring 32 to effect the closing of armature 24 and contact 33. The circuit for coil 26 is obtained from wire 23, junction 25, coil 26, wire 27, switch 28 and wire 29 to ground.

Switch 28 is, in this instance, shown to be connected by means of a suitable operating rod 30 to the clutch pedal 31 of the motor vehicle. The

control system of switch 28 is so constructed that when clutch pedal 31 is in the clutch-engaged position, switch 28 will be opened and when clutch pedal 31 is depressed to disengage the clutch, switch 28 will be closed, causing the energization of coil 26, which immediately attracts armature 24 to close the primary energizing circuit of coil 20.

It is not necessary to maintain clutch pedal 31 in the depressed position since upon the closing of armature 24 with contact 33, current will flow through wire 34, junction 35, auxiliary holding coil 36, wire 37 to ground which maintains armature 24 and contact 33 in the closed position until the circuit is broken by the opening of ignition switch 6.

The operation of the system is as follows: Upon closing ignition switch 6, current will flow from battery 1 through wire 3, ammeter 4, wire 5, switch 6, wire 7, coil 8 and to the distributor not shown, by way of wires 9 and return through ground to battery 1. Clutch pedal 31 is then depressed, closing switch 28, whereupon current will flow from battery 1 through wire 3, ammeter 4, wire 5, switch 6, junction 22, wire 23, junction 25, holding coil 26, wire 27, switch 28, wire 29 through ground and back to battery 1 through wire 2. Coil 26 being thus energized, attracts armature 24, causing the same to contact with contact 33 thereby allowing current to flow through wire 34, coil 36 and wire 37 to ground. Coil 36 being in parallel with coil 26, may now take up the function of maintaining armature 24 and contact 33 closed, and clutch pedal 31 may be released to open switch 28.

The closing of armature 24 and contact 33 will also permit current to flow from junction 35 through wire 38, coil 20, junction 39, wire 40, contacts 41 and 42 of vacuum relay 43 and to ground by way of wire 47. The energization of coil 20 closes switch 19 by bridging contacts 13 and 15 with switch member 14. Current will then flow from battery 1 through junction 10, wire 11, holding coil 12, contacts 13 and 15, wire 16, starting motor 17, wire 18 through ground and back to battery 1 through wire 2.

Starting motor 17 which may be mechanically connected to the internal combustion engine not shown, in any usual or well-known manner, then proceeds to crank the same. As the engine starts rotating, a partial vacuum is created within manifold 46 thereby withdrawing diaphragm 45 of vacuum relay 43 which allows contacts 41 and 42 to open, thus breaking the primary energizing circuit. Relay coil 20, however, does not become de-energized since the starting motor current drawn through holding coil 12 attracts armature 50 to effect closing of the secondary energizing circuit through coil 20 from junction 39, wire 48, contact 49, armature 50 and wire 52 to ground.

Starting motor 17 proceeds to crank the engine until it starts, whereupon the current drawn through holding coil 12 will decrease due to starting motor 17 being relieved of cranking the engine.

Upon a substantial decrease of the starting motor current, armature 50 is withdrawn from contact 49 by spring 51 and the energizing circuit to coil 20 is broken, allowing starting motor switch 19 to open. In the event, the engine stalls, substantially atmospheric pressure conditions are restored in manifold 46, and contacts 41 and 42 are closed by the action of spring 53 against diaphragm 45 thus closing the primary

energizing circuit for coil 20, and the starting operation is repeated.

A modified form of controller circuit is shown in Figure 2. However, the general arrangement, as shown in Figure 1 has been retained, and in order to avoid unnecessary repetition, like characters of reference will be applied to like circuits and parts. The ignition circuit is the same as previously described.

The starting motor circuit remains unchanged, with the exception that holding coil 12 has been omitted from line 11. Only one energizing circuit is provided for coil 20 of electromagnetic switch 19 which is controlled by a relay actuated in accordance with the generated voltage of the battery charging generator instead of the vacuum relay previously described.

The initial energization of coil 20 is, in this instance, also controlled by ignition switch 6 and a control relay comprising armature 24, contact 33 and holding coils 26 and 36. The clutch pedal controlled switch 28 is used in the same arrangement as previously described.

From coil 20, the energizing circuit thereof continues through wire 54, contact 55, armature 56 and wire 58 to ground. Armature 56 and contact 55 are normally held closed by coil springs 57 secured to armature 56. Holding coil 60 having one end connected to the ungrounded side of battery charging generator 62 and the other end grounded through wire 61, in conjunction with armature 56 and contact 55, constitutes a control relay actuated in accordance with voltage changes of the battery charging generator driven mechanically by the internal combustion engine.

A battery charging circuit is also shown comprising wire 64 leading from the ungrounded side of generator 62 through the usual battery charging cut-out or relay generally designated as 65, wire 66, junction 67, ammeter 4, wire 3, battery 1, wire 2, through ground and return to generator 62 by wire 63.

The operation of the modified system is as follows: Upon closing ignition switch 6, the ignition circuit is energized, as previously described, in connection with Figure 1. Current will not flow, however, in the energizing circuit of switch 19 until contact is made between armature 24 and contact 33. As soon as clutch pedal 31 is depressed, switch 28 will be closed, causing current to flow through wire 23, junction 25, holding coil 26, wire 27, switch 28 and wire 29 to ground.

Coil 26 attracts armature 24, closing the same with contact 33 which completes the circuit through wire 34, junction 35, holding coil 36 through wire 37 to ground. Clutch pedal 31 can now be released and switch 28 opened, since coil 36 maintains armature 24 and contact 33 in engagement. Current is now free to flow from junction 35, wire 38, coil 20, wire 54, contact 55, armature 56 and wire 58 to ground. Coil 20 being energized, closes switch 19 and current from battery 1 flows through wire 11, contacts 13 and 15, wire 16, starting motor 17, wire 18 to ground, through ground and back to battery 1.

Starting motor 17 then proceeds to crank the engine until it starts. As soon as the engine starts rotating, generator 62 starts building up its voltage. The building up process, however, is not instantaneous and the engine will have sufficient time to start before the voltage generated is high enough to cause sufficient current to flow through holding coil 60 to release armature 58 from the closed position. Then as the engine gets under way, current through coil 60 increases to such an

extent, that the pull of the coil overcomes the tension of spring 57, allowing the energizing circuit of coil 28 to be opened, whereupon switch 19 is opened and the starting motor 17 ceases to operate.

Should the internal combustion engine stall, the voltage of generator 52 would drop to zero, causing coil 68 to become de-energized and allowing armature 24 to engage contact 55, again closing the energizing circuit through coil 28 and repeating the starting operation. If the engine fails to start, all energizing circuits may be broken to stop the cranking operation by opening ignition switch 6.

15 In Figure 3 is shown a modified safety device in the form of a switch 68 to replace clutch operated switch 28 and which is controlled by gear shifting rods 69 in the transmission of the motor vehicle. With the exception of the energizing circuit from junction 22 to coil 28, the circuits and apparatus of Figure 3 are the same as those shown in Figure 1.

From junction 22, the energizing circuit continues through wire 23, junction 71, wire 70, armature 24, contact 33, wire 34, junction 35, wire 38, junction 77 to coil 28 and through either the primary or secondary branch circuits, as previously described.

30 Holding coil 36 for closing armature 24 with contact 33 is connected, as shown in Figure 1. Switch 68 is connected across armature 24 and contact 33 by means of wire 72 which taps into the circuit at 71 and connects to contact 73 and wire 76 connected to contact 75 and junction 77. 35 Switch member 74 is normally held in contact with contacts 73 and 75 by a spring 78 which may be positioned on the underside of gear case cover 79, as shown.

30 Switch member 74 may be mounted upon the upper end of an actuating rod 81 supported by a guide member 80 to permit vertical reciprocal motion thereof for the successive opening and closing of contacts 73 and 75. The lower end of rod 81 is preferably pivoted, as shown at 82, to a rocker arm 83. Rocker arm 83 is preferably placed at right angles to shifting rod 69 and adapted to rest in V-shaped notches shown at 84 provided therein. Notches 84 are so positioned as to be in alignment with rocker arm 83 when rods 69 are in the neutral position or in a position such that all driving connections in the transmission between the engine and running gear of the vehicle are broken. Now, as either of rods 69 is moved forward or back to place the engine 50 in gear with the running gear of the vehicle, rocker arm 83 will be raised and forced out of one of the notches 84 and which action raises actuating rod 81 carrying switch member 74 upward against spring 78 to effect opening of contacts 73 and 75.

When switch 68 is opened, there is no means for energizing and closing starting switch 19, thus preventing the starting of the engine with the automatic starter, while the vehicle is in gear.

65 When the gear shift rods are in the neutral position, switch 68 is closed. Then, as ignition switch 6 is closed, current will flow from battery 1, as previously described, to the ignition circuit and to junction 22. From junction 22, current will also flow through wire 23, junction 71, wire 72, contact 73, switch member 74, contact 75, wire 76, junction 77 through coil 28, as previously described, energizing the starting motor control switch. Current will also flow from junction 77

through wire 38, junction 35, coil 36 and wire 37 to ground.

The energization of coil 36 attracts armature 24 and effects engagement of the same with contact 33. Armature 24 and contact 33 are now in parallel with switch 68, whereupon switch 68 may be opened by the shifting of one of the rods 69 to place the motor vehicle in motion.

5 Armature 24 and contact 33 will remain closed to feed the energizing circuit of coil 28 in a manner previously described, until the entire contact circuit is broken simultaneously with the ignition circuit by the opening of switch 6. Switch 68 may also be employed in a semi-automatic starting system, as diagrammatically illustrated in Figure 4.

10 The usual ignition circuit from the battery is again shown including switch 6. The starting motor circuit including the starting motor switch 19, is similar to that shown in Figure 2. The 15 control circuit for switch 19 is, in this instance, not automatic but may be classified as being of the semi-automatic type.

From junction 22, the energizing circuit continues by way of wire 86, junction 88, wire 98, 25 armature 92, contact 94, junction 100, wire 99, switch 96, coil 28 and wire 97 to ground. The control of switch 96 is manual and may be conveniently located in the operating compartment 30 of the motor vehicle. Switch 68 operated as 35 previously described in connection with shift rods 69, prevents the closing of the energizing circuit of coil 28 of switch 19 until the transmission is in a neutral position. In this instance, switch 68 is connected from contact 75 through wire 87, coil 39 to junction 88 and from contact 73 through wire 85 to ground.

An operator attempting to start his vehicle, will first close ignition switch 6 and then switch 96. If gear shift rods 69 are not in the neutral 40 position, switch 68 will be opened and the energizing circuit for coil 28 cannot be closed due to the normally open circuit at armature 92 and contact 94. Upon placing gear shift rods 69 in the neutral position, switch 68 is closed in a manner previously described, allowing current to flow from junction 22, wire 86, junction 88, coil 99, wire 87, contact 75, switch member 74, contact 73 and wire 85 to ground. Coil 99 being thus energized, attracts armature 92 to engage the same 45 with contact 94. Current will then flow through junction 100, coil 95, and through wire 99 to ground. Coils 95 and 99 are now connected in parallel and both exert an attractive force on armature 92. Switch 96 may be now opened if 50 desired as will be the case upon the subsequent movement of the gear shift rods or the clutch pedal to place the vehicle in motion. Now, switch 96 may be closed and the circuit will be completed from junction 22, wire 86, wire 98, armature 92, contact 94, junction 100, wire 99, switch 96, coil 28, and wire 97 to ground.

The energization of coil 28 closes switch 19, thereby energizing the starting motor circuit, as previously described. Starting motor 17 then 55 proceeds to crank the engine in the usual manner.

As the engine starts, switch 96 may be opened by the operator, thereby de-energizing coil 28 and allowing switch 19 to open. The opening of 60 ignition switch 6 also de-energizes all starting control circuits.

From the foregoing disclosure, it is seen that a motor vehicle equipped with an automatic controlled starter system of the class described, 75

cannot be driven by the engine during the starting operation, should the vehicle have been left in gear, because the starting motor circuit cannot be energized until the operator first depressed the 5 clutch pedal or places the gear shift lever in a neutral position.

It is to be understood that the clutch-controlled switch 28 may also be employed in any of the other circuits illustrated and that the 10 transmission controlled switch 68 may likewise be used in those systems illustrating clutch control with equal effect.

I, therefore, do not wish to limit myself to the specific arrangements of safety switch operation 15 herein illustrated, as other arrangements incorporating changes and modifications of the above may be utilized, without departing from the spirit and scope of the appended claims.

I claim:

20 1. The combination with an internal combustion engine of a motor vehicle including a running gear and a movable member operable at will for controlling the transmission of power from the engine to the running gear of the vehicle, a 25 of a starting motor for cranking said engine, a normally broken starting motor circuit, an electro-magnetic switch for closing the starting motor circuit and including a coil, a normally broken energizing circuit for said coil, means controlled 30 by said movable member for closing said energizing circuit, means independent of said first-named means for maintaining said energizing circuit closed until the engine starts to operate under its own power, and further means operating 35 independently of the coupling between the engine and its working load for rendering said energizing circuit operative should the engine stall after being properly started.

2. The combination with an internal combustion 40 engine of a motor vehicle including a running gear and a movable member operable at will for controlling the transmission of power from the engine to the running gear of the vehicle, of a starting motor for cranking said engine, a normally 45 broken starting motor circuit, an electro-magnetic switch for closing the starting motor circuit and including a coil, a normally broken energizing circuit for said coil, means controlled 50 by said movable member for closing said energizing circuit, means independent of said first-named means for maintaining said energizing circuit closed until the engine starts to operate under its own power, additional means for making 55 and breaking said energizing circuit, and further means operating independently of the coupling between the engine and its working load for rendering said energizing circuit operative should the engine stall after being properly started.

3. The combination with an internal combustion 60 engine of a motor vehicle including a running gear and a movable member operable at will for controlling the transmission of power from the engine to the running gear of the vehicle, of a starting motor for cranking said engine, a normally 65 broken starting motor circuit, an electro-magnetic switch for closing the starting motor circuit and including a coil, a normally broken energizing circuit for said coil, means controlled 70 by said movable member for closing said energizing circuit, means independent of said first-named means for maintaining said energizing circuit closed until the engine starts to operate under its own power, additional means actuated in accordance with engine conditions for 75 making and breaking said energizing circuit, and

further means operating independently of the coupling between the engine and its working load for rendering said energizing circuit operative should the engine stall after being properly started.

4. The combination with an internal combustion engine, of a motor vehicle including a running gear and a movable member operable at will for controlling the transmission of power from the engine to the running gear of the vehicle, of a starting motor for cranking said engine, a normally broken starting motor circuit, an electro-magnetic switch for closing the starting motor circuit and including a coil, a normally broken energizing circuit for said coil including primary and secondary branch circuits, means controlled by said movable member for closing said energizing circuit, means actuated in accordance with engine conditions for making and breaking said primary circuit, and means actuated in accordance with the current flowing in the starting motor circuit for making and breaking said secondary circuit.

5. The combination with an internal combustion engine, of a motor vehicle including a running gear and a movable member operable at will for controlling the transmission of power from the engine to the running gear of the vehicle, of a starting motor for cranking said engine, a normally broken starting motor circuit, an electro-magnetic switch for closing the starting motor circuit and including a coil, a normally broken energizing circuit for said coil, means controlled by said movable member for closing said energizing circuit, means independent of said first-named means for maintaining said energizing circuit closed until the engine starts to operate under its own power, a battery charging generator operatively connected to said engine, and additional means actuated in accordance with the voltage generated by said generator for making and breaking said energizing circuit.

6. The combination with an internal combustion engine of a motor vehicle including a running gear and a movable member operable at will for controlling the transmission of power from the engine to the running gear of the vehicle, of an ignition circuit for said engine, a starting motor for cranking said engine, a normally broken starting motor circuit, an electro-magnetic switch for closing said starting motor circuit and including a coil, a normally broken energizing circuit for said coil connected in parallel with said ignition circuit, a switch for making and breaking said ignition and said energizing circuits, means controlled by said movable member for closing said energizing circuit, means independent of said first-named means for maintaining said energizing circuit closed until the engine starts to operate under its own power, and further means operating independently of the coupling between the engine and its working load for rendering said energizing circuit operative should the engine stall after being properly started.

7. The combination with an internal combustion engine of a motor vehicle including a running gear and a movable member operable at will for controlling the transmission of power from the engine to the running gear of the vehicle, of an ignition circuit for said engine, a starting motor for cranking said engine, a normally broken starting motor circuit, an electro-magnetic switch for closing said starting motor circuit and including a coil, a normally broken energizing circuit for said coil connected in par-

parallel with said ignition circuit, a switch for making and breaking said ignition and said energizing circuits, means controlled by said movable member for closing said energizing circuit, means 5 independent of said first-named means for maintaining said energizing circuit closed until the engine starts to operate under its own power, additional means for making and breaking said energizing circuit, and further means operating 10 independently of the coupling between the engine and its working load for rendering said energizing circuit operative should the engine stall after being properly started.

8. The combination with an internal combustion engine of a motor vehicle including a running gear and a movable member operable at will for controlling the transmission of power from the engine to the running gear of the vehicle, of an ignition circuit for said engine, a starting motor for cranking said engine, a normally broken starting motor circuit, an electromagnetic switch for closing said starting motor circuit and including a coil, a normally broken energizing circuit for said coil connected in parallel with said ignition circuit, a switch for making and breaking said ignition and said energizing circuits, means controlled by said movable member for closing said energizing circuit, means independent of said first-named means for maintaining said energizing circuit closed until the engine starts to operate under its own power, additional means actuated in accordance with engine conditions for making and breaking said energizing circuit, and further means operating 25 independently of the coupling between the engine and its working load for rendering said energizing circuit operative should the engine stall after being properly started.

9. The combination with an internal combustion engine, of a motor vehicle including a running gear and a movable member operable at will for controlling the transmission of power from the engine to the running gear of the vehicle, of an ignition circuit for said engine, a starting motor for cranking said engine, a normally broken starting motor circuit, an electromagnetic switch for closing said starting motor circuit and including a coil, a normally broken energizing circuit for said coil connected in parallel with said ignition circuit and including primary and secondary branch circuits, a switch for making and breaking said ignition and said energizing circuits, means controlled by said movable member for closing said energizing circuit, means actuated in accordance with engine conditions for making and breaking said primary circuit, and means actuated in accordance with the current flowing in the starting motor circuit for making and breaking said secondary circuit.

10. The combination with an internal combustion engine, of a motor vehicle including a running gear and a movable member operable at will for controlling the transmission of power from the engine to the running gear of the vehicle, of an ignition circuit for said engine, a starting motor for cranking said engine, a normally broken starting motor circuit, an electromagnetic switch for closing said starting motor circuit and including a coil, a normally broken energizing circuit for said coil connected in parallel with said ignition circuit, a switch for making and breaking said ignition and said energizing circuits, means controlled by said movable member for closing said energizing circuit, means

independent of said first named means for maintaining said energizing circuit closed until the engine starts to operate under its own power a battery charging generator operatively connected to said engine, and additional means actuated in accordance with the voltage generated by said generator for making and breaking said energizing circuit.

11. The combination with an internal combustion engine, of a motor vehicle including a running gear and a movable member operable at will for controlling the transmission of power from the engine to the running gear of the vehicle, of an ignition circuit for said engine, a starting motor for cranking said engine, a normally broken starting motor circuit, an electromagnetic switch for closing said starting motor circuit and including a coil, a normally broken energizing circuit for said coil connected in parallel with said ignition circuit, a switch for making and breaking said ignition and said energizing circuits, a normally broken control circuit for closing said energizing circuit, and means controlled by said movable member for closing said control circuit and means independent of said first named means for maintaining said energizing circuit closed until the engine starts to operate under its own power.

12. The combination with an internal combustion engine of a starting motor, a normally broken circuit for said motor, means for closing said circuit upon completion of the ignition circuit, means for rendering said closing means inoperative when the engine is coupled to its working load before the starting circuit is completed and additional means operating independently of the coupling between the engine and its working load for rendering said closing means operative should the engine stall after being properly started.

13. The combination with an internal combustion engine of a starting motor, a normally broken circuit for said motor, means for closing said circuit upon the completion of the ignition circuit of said engine, clutch operating means for coupling said engine with its working load, means actuated by said clutch operating means for rendering said closing means inoperative when the engine is coupled to its working load before the starting circuit is completed and additional means operating independently of said clutch operating member for rendering said closing means operative should the engine stall after being properly started.

14. The combination with an internal combustion engine of a starting motor, a normally broken circuit for said motor, a clutch actuating pedal for coupling said engine with its working load, a control circuit for closing said starting motor circuit upon the completion of the ignition circuit including a switch attached to said clutch pedal and adapted to be closed when the clutch is disengaged and an additional switch adapted to be automatically closed when the clutch is disengaged for rendering said control circuit operative independent of said clutch operated switch as long as the ignition circuit is closed.

15. The combination with an internal combustion engine of a starting motor, a normally broken circuit for said motor, a gear shift mechanism for coupling said engine to its working load through a transmission, a control circuit for closing said starting motor circuit including a switch attached to said gear shift mechanism and adapted to be closed when the gears are in neutral and an additional switch adapted to be auto-

- matically closed when the gears are in neutral for rendering said control circuit operative until the engine starts regardless of the position of the gear shift mechanism.
- 5 16. The combination with an internal combustion engine of a starting motor, a normally broken circuit for said motor, a control circuit for closing said starting motor circuit upon the completion of the ignition circuit, means for 10 rendering said control circuit inoperative when the engine is coupled to its working load before the starting circuit is completed, and means for rendering said control circuit operative should the engine stall after being properly started, said 15 last-named means being independent of the coupling between the engine and its working load.
17. In combination with an internal combustion engine and a power transmission mechanism therefor, starting mechanism for said engine, 20 means for preventing the initial operation of the starting mechanism when the engine is connected to a load by said transmission mechanism, and means whereby after initial actuation of the starting mechanism said starting mechanism 25 may be reactivated irrespective of the condition of the transmission mechanism.
18. In combination with an internal combustion engine having a power transmission mechanism, a starting mechanism and an electrical 30 system including a control switch, means for automatically energizing the starting mechanism upon closure of the control switch, means for preventing such energization when the power transmission mechanism is in operative condition, and means for automatically energizing 35 the starting mechanism in case of engine stall irrespective of the operative condition of the transmission mechanism.
19. In combination with an internal combustion engine having a power transmission mechanism, a starting mechanism and an electrical 40 system including a control switch, means for automatically energizing the starting mechanism upon closure of the control switch, means for preventing such energization when the power transmission mechanism is in operative condition 45 and means responsive to adjustment of the trans-
- mission mechanism into inoperative position while the control switch is closed for rendering said preventing means ineffective.
20. In combination with an internal combustion engine having a power transmission mechanism, a starting mechanism and an electrical system including a control switch, means for automatically energizing the starting mechanism upon closure of the control switch, means for preventing such energization when the power transmission mechanism is in operative condition, means responsive to adjustment of the transmission mechanism into inoperative position while the control switch is closed for rendering said preventing means ineffective, said 10 means thereupon retaining said preventing means ineffective irrespective of the adjustment of the transmission mechanism.
21. In combination with an internal combustion engine having a variable speed power transmission mechanism and an electrical starting system, means including a control circuit for automatically energizing said starting mechanism, a manual switch for opening and closing said control circuit, a switch in series with said 20 manual switch for opening said circuit responsive to engagement of the transmission mechanism, a switch in shunt with said transmission controlled switch, and means for closing said shunt switch 25 in response to closure of the control circuit.
22. In combination with an internal combustion engine having a variable speed power transmission mechanism and an electrical starting system, means including a control circuit for automatically energizing said starting mechanism, a manual switch for opening and closing said control circuit, a switch in series with said manual switch for opening said circuit responsive to engagement of the transmission mechanism, a switch in shunt with said transmission controlled switch, and an electro-magnetic coil 30 energized from said control circuit for closing said shunt switch and holding it closed until the control circuit is broken by opening the manual 35 switch.
